UNITED STATES PATENT OFFICE.

LIONEL JAMES BAKER BLAKE, OF BISHOPS STORTFORD, ENGLAND.

MIXING MACHINE.

Application filed September 24, 1926, Serial No. 137,579, and in Great Britain November 7, 1925.

The invention relates to improvements in mixing machines for concrete, tarmacadam and the like and refers not only to the portable type of apparatus commonly used in connection with road making and building construction, but also to apparatus for mixing glass batch, chemical and other mixtures. The object of the present invention is to provide a new and improved method of mixing the materials, improved means for delivery of the materials to be mixed into the mixing machine and means to facilitate the discharge of the mixed aggregate or agglomeration.

According to the present invention the mixer comprises a cylindrical drum or casing that is normally stationary and preferably in halves bolted together provided with charging and discharging orifices, mounted on a rotating axis or shaft and capable of partial rotation for emptying the contents thereof said shaft carrying mixing scoops of a similar section to that of the well known elevator bucket the forward edges of said scoops extending practically the entire length of the interior of the drum within which they rotate whilst the rear edge is shorter and situated away from the axis or shaft to which they are secured so as to leave a space between said rear edge and the shaft for the aggregate to fall when the scoops are successively elevated by the act of rotation and thereby obtain a cataract-like action of the agglomeration to be mixed.

A mixing machine of the type described embodying the improvements set out is illustrated in the accompanying three sheets of drawings in which,

Figure 1 is an elevation from the rear.

Figure 2 a side elevation as viewed from the right hand of Figure 1.

Figure 3 a transverse section of the drum or casing showing the rotatable mixing scoops in end elevation.

Figure 4 a sectional elevation taken on line $\alpha-\alpha$ of Figure 3 incorporating parts shown in Figure 1.

Figure 5 is a detail in connection with the construction of the mixing scoop and

Figure 6 is a side elevation showing means for effecting the tilting operation for the discharge of the contents combined with a shock-absorbing device.

Referring now to the drawings in which similar reference characters relate to like parts in all the figures thereof, the mixer

comprises a cylindrical drum or casing a supported on the shaft b that is carried by suitable bearing standards or the like c which when mounted on the chassis d of a carriage or the like makes the machine portable. To the shaft b is attached a number of blades, paddles or scoops e which are caused to rotate inside the drum or casing a whereby the materials are lifted and mixed within the said drum which during the mixing operation remains stationary.

The blades, paddles or scoops e are of peculiar construction and designed to obtain a cataract-like action of the aggregate or agglomeration to be mixed and instead of as heretofore employing several rotatable arms with blades fixed to their ends it has been found to be considerably more efficient to make the blades or scoops of a similar cross section to that of the well known elevator bucket as shown in the drawings the forward edge f of said scoop extending practically the entire length of the drum a within which it rotates the rear edge g or that near to the axis being shorter and secured to spider frames h away from the shaft b so as to leave a space i between the shaft b and the rear edge g of the scoop e for the material to fall when the scoop e is elevated by the act of rotation, the ends j of the scoop being thus inclined a natural tendency to throw the materials towards the centre of the drum is also produced. According to the capacity of the machine so is the number of the scoops e increased or decreased as the case may be and in the small size machine even two would suffice but obviously a better balancing effect is obtained by the employment of three by which also means are afforded for stiffening the structure by stay rods k connecting the several ends together circumferentially.

Preferably the forward edge of the scoop e is provided with replaceable serrated bevelled metal strips m see Figures 4 and 5, to minimize the detrimental effect caused by hard pieces of the aggregate jamming between the edge of the scoop e and the drum a such serrated bevelled surfaces sufficing usually for the easy removal or turning over of such obstacles that would otherwise cause damage to the machine. The serrated bevelled metal strips m may be provided with a rearward extension m' that practically fills up the wedge-shaped space between the scoop e and the interior surface of the drum a but obviously

such extensions or blocks m' may be separate and distinct from the strips m . For mixing some materials the replaceable metal strips may be dispensed with.

5 The drum or casing a is preferably made in halves bolted together and for convenience they may be hereinafter referred to as the upper and lower halves a' a^2 respectively.

10 The upper half a' of the casing or drum a is provided with two openings, one n for charging the material to be mixed and the other o for discharging the mixed agglomeration. These openings may be fitted with suitable doors or covers, independently or 15 automatically operated but doors or covers are not essential, and are therefore omitted from the drawing.

15 The mixer may be fitted with a feed spout, batch hopper or sideloader. In the latter 20 case of the employment of a sideloader as illustrated in the drawing this is formed as a scoop or container p with extended arms q that are capable of rotation about the main shaft b of the drum or casing a , and can be 25 hoisted into the charging position as shown in dotted line Figure 2 by means of a quadrant, or quadrants r mounted outside the drum a on the shaft b and attached to the extended arms q of the scoop p , the quadrants r being 30 caused to rotate and hoist the charging scoop p by means of suitable gearing and clutch gear in connection with the driven shaft of the engine.

35 In the arrangement shown in the drawing it will be seen that the prime mover is the internal combustion engine 1 which through bevel gear 2 imparts rotatory motion to the driven shaft 3 which by sprocket pinion 4 the female part of clutch sprocket 5 is driven by 40 an ordinary drive chain 6. To the clutch sprocket 5 is fixed the sprocket wheel 7 which with the aid of chain 8 imparts continuous rotatory motion to the shaft b by the sprocket wheel 9. The rotatory motion of the sprocket 45 wheel 10 is governed by the male half 11 of the clutch that is operable by the hand lever 12 which synchronously releases or applies the band brake 13 in the well known manner. The sprocket 10 by the chain 14 drives sprocket wheel 15 on shaft 16 that carries the pinions s which mesh with the quadrants r .

50 It will be clear from the foregoing description that to charge the machine the feed scoop p is filled with the necessary materials and then raised into the elevated position by the manipulation of the operating lever 12 whereby the pinions 5 are rotated and operate the quadrants r so that the contents of the scoop will be delivered or fall into the drum through 55 the charging orifice n . After the charging has been effected the scoop p is lowered back into its lowermost position for refilling by manipulation of the operating lever 12 with the aid of the brake mechanism 13. The shaft 60 b of the mixer (carrying the scoops) rotates 65

continuously mixing the materials and assisting in the discharge of the same when the mixing is completed.

On the completion of the mixing the drum a is rotated through a suitable angle which 70 can be readily effected by hand or may be effected by suitable gearing so that the contents of the drum is discharged from the discharge orifice o which is preferably of spout formation as shown.

75 Referring now to Figure 6 which illustrates mechanism for effecting the partial rotation of the drum for discharging purposes combined with means for absorbing shock due to jamping as aforesaid the manually operated spindle 16 is disposed longitudinally of the drum a and provided with a crank handle 17. This spindle or shaft 16 is supported in bearings 18 fixed to the end standards and carries a pair of drums 19 upon which wire ropes 20 are wound in such a manner that their free ends 21 and 22 may be attached to eye-bolts 23 that pass through brackets 24 fixed on the exterior of the drum a the bolts 23 forming the supports for helical springs 25 that rest upon the brackets 24 so that presuming the operating spindle 16 to be locked by a catch associated with the crank handle 17 a limited amount of oscillatory movement is permissible of the drum a . The tension 90 of the springs 25 is regulated by the manipulation of the nuts 26 on the eye-bolts 23 in the known manner.

95 In the foregoing description it has been presumed that the machine is of the self-contained portable type the internal combustion engine 1, being mounted on the carriage or chassis d beneath the drum a of the mixer, said engine driving a counter shaft by which the mixing paddles are rotated and the hoist-gear set in action by the clutch mechanism as and when required. Obviously where the mixer is used as a stationary machine it may be driven by any convenient means i. e. electric motor, fast and loose pulleys, or hand power.

100 Furthermore the mixer as above described may be employed in combination with one or more drying drums, of similar construction and provided with a furnace when dealing with tarmacadam or other bituminous mixtures, the whole combination being mounted 115 on a suitable frame and constituted as portable or stationary apparatus as desired.

110 What I claim is:—

120 1. A mixing machine for concrete, tarmacadam and the like comprising a normally stationary mixing drum provided with charging and discharging orifices, a shaft on which said drum is mounted, a plurality of mixing scoops carried on said shaft within said drum and means for imparting a continuous rotation to said shaft whereby said scoops are successively elevated, the forward edges of said scoops 125 extending practically the entire length of the 130

interior of said drum and the rear edges thereof being of lesser length than said forward edges and situated away from said shaft, inclined ends connecting said forward and rear edges of said scoops, and means for tilting said drum to discharge the mixed material.

2. A mixing machine for concrete, tarmac-adam and the like comprising a normally stationary drum provided with charging and discharging orifices, a shaft on which said drum is mounted, a plurality of spider frames secured to said shaft within said drum and a plurality of mixing scoops carried by said frames, stay bars connecting the ends of said scoops, means for imparting a continuous rotation to said shaft whereby said scoops are successively elevated, the forward edges of said scoops extending practically the entire length of the interior of said drum and the rear edges being of lesser length than said forward edges and secured to said spider frames, inclined ends connecting said forward and rear edges of said scoops, and means for tilting said drum to discharge the mixed material.

3. A mixing machine for concrete, tarmac-adam and the like comprising a normally stationary mixing drum provided with charging and discharging orifices, a shaft on which said drum is mounted, a plurality of mixing scoops carried on said shaft within said drum and means for imparting a continuous rotation to said shaft whereby said scoops are successively elevated, the forward edges of said

scoops extending practically the entire length of the interior of said drum and the rear edges thereof being of lesser length than said forward edges and situated away from said shaft, inclined ends connecting said forward and rear edges of said scoops, replaceable 40 rated metal strips secured to said forward edges of said scoops, and means for tilting said drum to discharge the mixed material.

4. A mixing machine for concrete, tarmac-adam and the like comprising a normally stationary mixing drum provided with charging and discharging orifices, a shaft on which said drum is mounted, a plurality of mixing scoops carried on said shaft within said drum and means for imparting a continuous rotation to 50 said shaft whereby said scoops are successively elevated, the forward edges of said scoops extending practically the entire length of the interior of said drum and the rear edges thereof being of lesser length than said forward 55 edges and situated away from said shaft, inclined ends connecting said forward and rear edges of said scoops, a shaft carried longitudinally of said mixing drum, a handle for operating said shaft, drums carried on said shaft, wire ropes wound upon said drums, eyebolts to which the free ends of said ropes are attached, springs surrounding said eyebolts and a catch for locking said handle in its inoperative position.

In testimony whereof I affix my signature.

LIONEL JAMES BAKER BLAKE.
